(57) **CLAIM**

The ornamental design for a toilet paper caddy with hexagonal design, as shown and described.

DESCRIPTION

FIG. 1 is a perspective view of a toilet paper caddy with hexagonal design in accordance with my design;

FIG. 2 is a front elevational view of the toilet paper caddy with hexagonal design of FIG. 1;

FIG. 3 is a rear elevational view thereof;

FIG. 4 is a bottom plan view thereof;

FIG. 5 is a top plan view thereof; and,

FIG. 6 is a side elevational view as viewed from the right side of FIG. 2, with the left side elevational view being a mirror image thereof.
